US00D759797S

(12) **United States Design Patent**
Farone

(10) **Patent No.:** **US D759,797 S**
(45) **Date of Patent:** **** Jun. 21, 2016**

(54) **TABLE TOP AIR PURIFIER**

(71) Applicant: **Guardian Technologies LLC**, Mentor, OH (US)

(72) Inventor: **Richard C. Farone**, Willoughby, OH (US)

(73) Assignee: **Guardian Technologies LLC**, Euclid, OH (US)

(**) Term: **15 Years**

(21) Appl. No.: **29/544,293**

(22) Filed: **Nov. 2, 2015**

Related U.S. Application Data

(62) Division of application No. 29/464,149, filed on Aug. 13, 2013, now Pat. No. Des. 745,128.
